[57] CLAIM

The ornamental design for a telephone apparatus, as shown and described.

DESCRIPTION

FIG. 1 is a top front left side perspective view of our invention;
 FIG. 2 is a top plan view;
 FIG. 3 is a front view;
 FIG. 4 is a rear view;
 FIG. 5 is a left side view;
 FIG. 6 is a right side view;
 FIG. 7 is a top, front left side perspective view of a second embodiment of that shown in FIG. 1;
 FIG. 8 is a top plan view;
 FIG. 9 is a front view;
 FIG. 10 is a rear view;
 FIG. 11 is a left side view; and,
 FIG. 12 is a right side view.
